UNITED STATES PATENT OFFICE

2,626,327

RADIO-CLOCK-LAMP COMBINATION

Burdette B. Gilmore, Pelham Manor, N. Y.

Application August 1, 1950, Serial No. 176,950

5 Claims. (Cl. 200—36)

1

It is among the objects of the invention to provide a radio-clock-lamp combination that may readily be incorporated in a single unit which is neat, compact and devoid of any unsightly wiring, which unit has but few parts that may readily be assembled and are not likely to become deranged, the controls of the radio portion of the unit being readily accessible for tuning or controlling the volume from a plurality of sides thereof and the clock portion of the unit indicating the time also on a plurality of sides of said unit.

According to one aspect of the invention, the unit comprises a hollow, preferably elongated casing in which the radio, the clock and the lamp are all contained, preferably in superposed relation, with the lamp portion desirably being located at the top of the casing. The radio desirably is controlled by a plurality of dials and the dial which controls the tuning of the radio is desirably arranged so that one-quarter revolution thereof will rotate the tuning condenser of the radio through a complete cycle. Desirably the dial is exposed at four positions with respect to the casing and carries four sets of station indicators thereon so that the radio may be tuned from any side of the casing. The clock portion of the unit desirably comprises a clock motor which rotates a drum having an annular face extending parallel to the wall of the casing. The annular face of the drum is desirably exposed through a plurality of apertures in said wall; and the face has a plurality of sets of dial markings thereon, visible respectively, through each of said apertures.

In the accompanying drawings, in which are shown one or more of various possible embodiments of the several features of the invention,

Fig. 1 is a fragmentary side elevational view of the unit with parts broken away,

Fig. 2 is a longitudinal detail view taken along line 2—2 of Fig. 1,

Fig. 3 is a transverse view taken along line 3—3 of Fig. 1,

Fig. 4 is a longitudinal sectional view taken along the line 4—4 of Fig. 1,

Fig. 5 is a sectional view on an enlarged scale showing the clock mechanism,

Fig. 6 is a transverse sectional view taken along line 6—6 of Fig. 4,

Fig. 7 is a view similar to Fig. 6 taken along line 7—7 of Fig. 5, and

Fig. 8 is a circuit diagram of the unit.

Referring now to the drawings, the unit desirably comprises an elongated hollow casing 11

2

of any suitable material such as plastic, and preferably having a plurality of supporting feet 12, which desirably are molded integral with the casing and serve to support the latter in upright position.

The wall 13 of the casing desirably has a plurality of grills 14 therein to provide access for the sound from the loud-speaker 15 of the radio receiver 16, positioned in the casing and supported therein in any suitable manner. As any conventional receiver may be used, the construction thereof will only be described to the extent necessary for a clear understanding of the invention.

The receiver 16 desirably has two vertical shafts 17 and 18, which control the volume and the tuning capacitor of the radio, respectively. Although shafts 17 and 18 could be mounted in any suitable manner, they are illustratively shown as being transversely displaced from each other and means are desirably provided to rotate shafts 17 and 18 from any side of the casing 11.

To this end, as shown in Fig. 4, the lower portion of the casing 11 desirably has an annular, upstanding flange 21 therein desirably cast integral therewith. Securely mounted on the top surface of flange 21 is a plate 22, which supports the control mechanism for the shafts 17 and 18.

As shown in Fig. 4, the plate 22 has an axial bearing sleeve 23 rigid therewith through which extends the volume control drive shaft 24. Affixed on the upper end of drive shaft 24, which extends through plate 22, is a gear 25 spaced from the plate 22 by a washer 26, said gear 25 meshing with a pinion 27 affixed to volume control shaft 18. The ratio of gear 25 to pinion 27 is desirably such that one-half of a revolution of the shaft 24 will turn the volume control shaft 18 one revolution.

In order to rotate shaft 24, a horizontal control dial 28 is desirably affixed to the lower end thereof. The shaft 24 is of such length that it extends below annular flange 21 and peripheral portions of the horizontal control dial 28 are exposed between adjacent pairs of feet 12. The diameter of the dial 28 is such that the periphery thereof will extend outwardly of such feet as shown in Figs. 1 and 4. Thus, the dial 28 is readily accessible for rotation from any of the four sides of the casing.

Encompassing bearing sleeve 23 is a second bearing sleeve 31, which desirably has a flange 32 at the lower end thereof seated on a nut 33, encompassing shaft 24 and threaded on the end of

sleeve 23 abutting against the shoulder 23 thereof, said nut being spaced from the top surface of dial 28. The upper end of sleeve 31 which lies below plate 22, being spaced therefrom by a washer 34, has a gear 35 affixed thereon, which meshes with a pinion 36 affixed on the lower end of tuning shaft 17. The ratio of gear 35 to pinion 36 is desirably such that one-quarter revolution of the bearing sleeve 31 will rotate the capacitor (not shown) in the radio controlled thereby through a complete tuning cycle.

In order to rotate sleeve 31, a second horizontal control dial 37 is desirably affixed to the flange end thereof. Dial 37 is desirably the same size as dial 28, being spaced therefrom by the nut 33 so that the two dials may be rotated independently of each other. Thus, the peripheries of both dials 28 and 37 are readily accessible between adjacent portions of feet 12 for tuning the radio and controlling the volume thereof.

As it requires only one-quarter of a revolution of the dial 37 to rotate shaft 17 through a complete tuning cycle, the periphery of dial 37 is desirably provided with four sets of station selector markings. Each set of markings occupies 90 degrees of the dial, and will be exposed, respectively, between each of the pairs of adjacent feet 12 on the four sides of the casing so that, for example, if the unit should be placed on a night table between two beds, the occupant of either bed may tune the radio, or the radio may be tuned from the front or the rear, if desired.

To mount the clock assembly which as shown in Figs. 4 and 5 is desirably positioned near the top of the casing, the latter desirably has an internal annular ledge 41, near the upper end thereof, which supports a base plate 42. A plurality of upright supports or posts 43 are desirably affixed at their lower ends as at 44 to said base plate, said posts 43 carrying a second plate 45 extending parallel to base plate 42 and affixed to the upper ends of the posts. An additional plate 46 is provided mounted on posts 43 interposed between plates 42 and 45 and carrying the clock motor 47.

As shown in Fig. 5, the clock motor 47, which is of conventional type, has a depending vertical arbor 48 which desirably extends through a bore 51 in an insulating block 52 affixed in an opening 53 in plate 46, the end of said arbor also extending through an axial bearing opening 54 in base plate 42. Frictionally retained on arbor 48 between plates 42 and 46 is a split tube 55, which desirably has a laterally extending flange 56 at the lower end thereof which is rigidly affixed to the circular floor 57 of a drum 58, said floor 57 being spaced from base plate 42 by means of a washer 61 encompassing said arbor 48. The drum 58 desirably has an upstanding face 62 on the periphery of the floor 57 which extends parallel to the inner surface of the wall 13 of said casing 11 and said wall desirably has a plurality of apertures 63 therethrough, preferably four in number, arranged in diametrically opposed pairs to permit viewing of the surface of the face 62 of the drum from any side of the casing.

As shown in Fig. 4, face 62 has a plurality of sets of time indicators thereon illustratively four in number, arranged in two horizontal rows, each desirably having two sets of numerals scaled from 1 to 12, and occupying 180 degrees of said face, said sets being associated respectively with said apertures 63, each of which has a pointer 60 to indicate the time.

Means are desirably associated with the clock 75

motor 47 which, at a predetermined time, will close a circuit desirably to some electrical appliance which in the embodiment herein may be an alarm bell 65 positioned in the casing or the radio 16.

As shown in Fig. 5, such means desirably comprises a gear 66 encompassing an annular reduced portion 67 at the bottom of insulating block 52, said gear being rotatably mounted on said annular portion, with the periphery 68 of said gear desirably extending beyond the periphery 69 of said block.

To prevent vertical displacement of said gear 66, an insulating washer 71 desirably encompasses said annular portion 67, said washer 71 and said gear 66 being retained in place by a contact plate 72 affixed to the under surface of block 52 as by bolts 73.

To electrically connect gear 66 to contact plate 72, a contact arm 76, which is desirably a leaf spring, is affixed at one end as at 77, to a pin 78 rigidly mounted on and depending from gear 66 adjacent the periphery 68 thereof. The free end of said leaf spring 76 is positioned so as to be resiliently urged against and to ride on the periphery 81 of a disc 82 of insulated material rigidly affixed to tube 55. The disc 82 is desirably slightly greater in diameter than the contact plate 72, thereby normally retaining the free end of the leaf spring spaced from the periphery of said contact plate. Desirably, the insulated disc 82 has a notch 83 in its periphery, of sufficient depth so that when the free end of the spring 76 enters such notch in the manner hereinafter to be described, such free end will engage the periphery of contact plate 72, thereby to be electrically connected thereto, said leaf spring and said contact plate functioning as a switch.

In order to provide an electrical connection to the gear 66, a pin 87, slidably mounted in a bore 88 in block 52 is resiliently urged against the face of gear 66 by a leaf spring 86 affixed at its free end as by screw 85 to block 52.

Means are desirably provided to rotate gear 66 so that the relative position of spring 76 with respect to the notch 83 may be changed to permit regulation of the time at which the spring 76 will engage contact plate 72.

To this end, the gear 66 meshes with a pinion 91 affixed at the end of shaft 92 extending through vertically aligned bearing openings 93 in plates 45 and 46. The upper end of shaft 92 which extends above plate 45 has a pinion 94 affixed thereon which meshes with a gear 95 rotatably mounted on a stud shaft 96 extending axially through plate 46. Shaft 96 also rotatably mounts a horizontal knob 97 to which the gear 95 is affixed so that upon rotation of the knob, the gear 95 will rotate therewith.

As shown in Figs. 3, 4 and 5, the knob 97 is positioned in a cover 101, also desirably of plastic, which is affixed to the top of the casing 11. The cover 101 desirably has a pair of diametrically opposed apertures 102 therein through which the periphery of knob 97 is exposed as shown in Figs. 2 and 3. The knob desirably has two sets of markings thereon each scaled from 1 to 12 and associated, respectively, with apertures 102.

The lamp portion of the unit desirably comprises a holder 105 preferably formed integral with the cover 101 and having a conventional bulb socket 106 thereon. The socket 106 is desirably controlled by a switch 107 also mounted on top of the cover 101 and connected in series with the socket and a source of current. To

complete the lamp portion of the unit a shade 111 is supported by the cover 101 preferably by means of a plurality of horizontal arms 108, affixed at one end by screws 109 to the cover 101 and at their free ends to the shade as at 112.

Although the clock, the radio and the lamp could be connected in any suitable manner, the circuit shown in Fig. 8 is preferred.

In this circuit, one side of the lamp socket 106 is connected by lead 114 to main 115 and the other side of the socket 116 is connected through switch 107 to main 117. The clock motor 47 is connected directly across mains 115 and 117 by leads 118 and 119 and lead 118 is connected to bolt 73 by nut 75 as shown in Fig. 5. Pin 87 is connected by lead 121 to one of the contacts 122 of switch 123 which is desirably mounted on top of the cover 101. Contact 127 of switch 123 is connected by lead 128 to one side of the input of alarm bell 65, the other side of said input being connected by lead 129 to main 115. One side of the input of the radio 16 is desirably connected to main 115 by lead 125 and the other side of the input of the radio is connected by lead 126 to contact 131 of switch 123. The circuit is completed by connecting contact 132 of switch 123 to main 117.

To use the unit, which for example may be positioned on a table between two beds, it is merely necessary to connect the mains 115, 117 to a wall outlet or other convenient source of current. This will energize the clock motor 47 to rotate arbor 48 and drum 58 thereon. Thus as the two horizontal rows of time markings on the face 62 of drum 58 pass by the four apertures 63 in the walls of the casing, the pointer 60 associated with each of said apertures will indicate the time.

If the time setting is incorrect, it may readily be adjusted by merely rotating the drum 58 with the finger with respect to the arbor 48. Such rotation of the drum is possible by reason of the frictional grip of the split type tube 55 which mounts the drum, the frictional hold being sufficient for the arbor to drive the drum, yet permits independent movement of one with respect to the other.

If the user should desire that the alarm bell 65 ring at a pre-selected time, it is merely necessary to rotate the dial 97 to the selected time setting through either of the apertures 102 in cover 101. As a result of the transmission from such dial through gear 95, pinion 94, shaft 92, pinion 91 and gear 66, the latter will rotate to move the contact arm 76 along the periphery of insulating disc 82. Thus, as the latter rotates under the drive imparted thereto by clock motor 47 and arbor 48, the notch 83 will be brought into alignment with said contact arm 76 so that the latter may engage contact plate 72.

If the movable contact arm 133 of switch 123 is engaging contacts 122 and 127, the alarm bell will be energized, the circuit being from main 117, lead 118 through bolt 73 and contact plate 72, contact arm 76, gear 66, pin 87, resilient arm 86, and lead 121 to fixed contact 122 of selector switch 123, thence from fixed contact 127 and lead 128 to one side of the alarm bell and from the other side of the alarm bell through lead 129 to main 115.

After the alarm bell has been energized, it may readily be turned off by merely turning the switch 123 to the "off" position in which movable contact 133 engages fixed contacts 131 and 132.

If the user should desire the radio 16 to turn

on at a preselected time, he need merely set the switch 123 so that the movable contact arm 133 engages fixed contacts 122 and 131. When contact arm 76 engages contact plate 72 a circuit will be completed to the radio 16. Such circuit is from main 117, lead 118 through bolt 73 and contact plate 72, contact arm 76, gear 66, pin 87, resilient arm 86, and lead 121 to fixed contact 122 of selector switch 123, thence through movable contact arm 133, fixed contact 131, lead 126 to one side of the input of radio 16 and from the other side of the input through lead 125 to main 115.

As the contact arm 76 will engage contact plate 72 for some time, which may be in the order of one hour, the radio will operate for this period. If the user should desire the radio to operate independently of the clock control, he need merely turn the selector switch 123 to the "off" position in which movable contact arm 133 will connect fixed contacts 131 and 132 to complete the circuit to the radio.

As dials 28 and 37 are accessible from either of the four sides of the unit, it is apparent that the radio may be regulated from any side without need for turning the unit around.

With the construction thus described, a neat, compact, multi-purpose unit is provided which is devoid of all unsightly wiring, requiring as it does, but a single extension cord for connection to a source of power. The unit may be used in any room of a house and is especially suited for use on a night table positioned between two beds in a bedroom, as it is readily accessible for operation of all of the components thereof by either of the occupants.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. An article of the character described comprising an elongated hollow casing, a supporting plate in said casing lying in a plane at right angles to the axis of said casing, an insulating block mounted on said supporting plate, said block having an axial bore therethrough, a clock motor mounted on said plate having an arbor extending through said bore, a drum mounted on said arbor, said drum having an annular face extending parallel to the wall of said casing, a plurality of sets of time indicators on said face, said casing having apertures in the wall thereof, each of said apertures being associated respectively with one of said sets of time indicators, a gear rotatably mounted on said block, a contact plate mounted on said block coaxial with said gear, insulating means spacing said contact plate from said gear, an insulated disk coaxial with said plate and rotatable with respect thereto by said motor, said disk having a diameter greater than that of said plate, and a contact arm carried by said gear, electrically connected thereto, and resiliently urged against the periphery of said disk, said disk having a notch in the periphery thereof, whereby when said disk is rotated to move said notch into alignment with said contact arm, the latter will enter said notch and engage said contact disk.

2. The combination set forth in claim 1 in which means are provided to rotate said gear thereby to change the relative position of said contact arm with respect to the notch in said disk.

3. The combination set forth in claim 1 in which a second supporting plate is provided above the first supporting plate and means are provided carried by said second supporting plate to rotate said gear thereby to change the position of said contact arm with respect to the notch in said disk, said means comprising a vertical shaft bearing in said plate and having a pinion affixed at each end thereof, the lowermost pinion meshing with said gear, a second gear rotatably mounted on said second supporting plate and meshing with said uppermost pinion and means to rotate said second gear.

4. An article of the character described comprising an elongated hollow casing, a supporting plate in said casing lying in a plane at right angles to the axis of said casing, an insulating block mounted on said supporting plate, said block having an axial bore therethrough, a clock motor mounted on said plate having an arbor extending through said bore, a split sleeve encompassing said arbor and driven thereby, a drum mounted on said sleeve, said drum having an annular face extending parallel to the wall of said casing, a plurality of sets of time indications on said face, said casing having apertures in the wall thereof, each of said apertures being associated respectively with one of said sets of time indicators, said block having an annular portion at the lower end thereof, a gear rotatably mounted on said annular portion, a contact plate mounted on the under surface of said annular portion coaxial

with said gear and insulated therefrom, an insulated disk coaxial with said plate affixed to said sleeve and rotatable therewith, said disk having a diameter greater than that of said contact plate whereby said disk is rotated by said motor to move said notch into alignment with said contact arm, the latter will enter said notch and engage said contact plate, and a contact arm carried by said gear, electrically connected thereto and resiliently urged against the periphery of said disk and having a notch in the periphery thereof extending inwardly of the periphery of said contact plate.

5. The combination set forth in claim 4 in which a contact pin is slidably mounted in a bore in said block, with the lower end of said pin riding on the surface of said gear, and means are provided resiliently to retain said pin in said bore.
